Bunn & Neuman
ATTORNEYS.

UNITED STATES PATENT OFFICE.

NATHAN NEUMAN, OF PHILADELPHIA, PENNSYLVANIA.

SWEATER.

Application filed August 23, 1927. Serial No. 214,807.

My invention relates to an improvement in sweaters and more particularly to that type of sweater known as a "shaker" sweater, having a large collar and lapels.

Heretofore in sweaters having large collars and which are intended to fit snugly at the back of the neck, it has been difficult to maintain a neat appearance at the base of the neck since the large collar tends to sag, more especially due to the elasticity of the knitted fabric of which the sweaters are made, and which gives to the weight of the collar and becomes distorted, with sagging of the collar, when strain is put on it over the shoulders.

strips *g* extend under the shoulder portions *h* from at or adjacent to the ends of the strip *f* to the top of the arm holes at the points *i* of the shoulders. The nonelastic strip *f* is secured as by sewing throughout a major portion of its length from its ends, its central portion *f'* being free and forming a hanger. The elastic strips *g* are free throughout the major portion of the length, being secured at or adjacent to their ends at or adjacent to the parts of the shoulder and at or adjacent to the ends of the strip *f*.

In the use of the sweater constructed as described, the nonelastic strip *f* will act to positively prevent lateral strains from distorting the base of the collar *d* and will also prevent the weight of the collar from causing it to sag away from the neck. The elastic strips *g* will yieldingly resist strain over the shoulders, permitting the shoulder portions of the sweater to accommodate themselves to fit a wearer and on release of strain will draw the shoulder portions back to normal. The nonelastic strip *f* and the elastic strips *g* will cooperate, the latter permitting and controlling strain over the shoulders respectively and the former resisting the transmission of strains between the shoulders at the base of the collar and preventing distortion and sagging of the collar.

Having now indicated in a general way the nature and purpose of my invention, I will proceed to a detailed description of a preferred embodiment thereof with reference to the accompanying drawing in which:

Figure 1 is a front view of the upper portion of a sweater embodying my invention in open position.

Figure 2 is a rear view of the upper portion of the sweater shown in Figure 1.

The sweater illustrated and which is made of knitted fabric comprises a back portion *a*, extensions of which form sides and front portions, provided with arm holes *b*, to which are secured sleeves *c*, a collar *d* and lapels *e*, which are respectively secured to a front edge of the body portion and at one end to an edge of the collar.

The upper edge of the back portion between the shoulders is recessed for the reception of the lower portion *d'* of the collar, the lower edge and lower portions of the sides of which are secured to the edges of the recess, as by knitting.

A strip of nonelastic material *f* is secured over the line of juncture of the lower edge of the collar and the back portion and elastic

strips *g* extend under the shoulder portions *h* from at or adjacent to the ends of the strip *f* to the top of the arm holes at the points *i* of the shoulders. The nonelastic strip *f* is secured as by sewing throughout a major portion of its length from its ends, its central portion *f'* being free and forming a hanger. The elastic strips *g* are free throughout the major portion of the length, being secured at or adjacent to their ends at or adjacent to the parts of the shoulder and at or adjacent to the ends of the strip *f*.

In the use of the sweater constructed as described, the nonelastic strip *f* will act to positively prevent lateral strains from distorting the base of the collar *d* and will also prevent the weight of the collar from causing it to sag away from the neck. The elastic strips *g* will yieldingly resist strain over the shoulders, permitting the shoulder portions of the sweater to accommodate themselves to fit a wearer and on release of strain will draw the shoulder portions back to normal. The nonelastic strip *f* and the elastic strips *g* will cooperate, the latter permitting and controlling strain over the shoulders respectively and the former resisting the transmission of strains between the shoulders at the base of the collar and preventing distortion and sagging of the collar.

Having now fully described my invention, what I claim and desire to protect by Letters Patent is:

In a sweater in combination, a body provided with arm holes and including back and shoulder portions, a collar joined to the back portion of the body, a strip of nonelastic material extending adjacent the line of juncture of the collar and body and elastic strips of elastic material extending from points adjacent the ends of said strip of nonelastic material to points adjacent the points of the shoulder portions, said elastic strips being secured adjacent their ends only, the intermediate portions of said strips being free.

In testimony of which invention, I have hereunto set my hand, at Philadelphia, Pennsylvania, on this 22nd day of August, 1927.

NATHAN NEUMAN.
